BLIND STITCHING APPARATUS

Sylvester J. Birginal, Omaha, Nebr.

Application July 8, 1944, Serial No. 544,051

9 Claims. (CL. 112—140)

1

This invention relates to blind stitching apparatus, and more particularly to an attachment for a conventional sewing machine adapted to convert it into a blind hemmer.

One feature of this invention is that it provides improved blind stitching apparatus; another feature is that the apparatus embodying this invention may be used in blind sewing work of flat or tubular design on the conventional sewing machine, preferably of the power or commercial type, without the need of a tubular knee, a special bed, or the like; still another feature of this invention is that it includes means for precision adjusting the position of means guiding the material being sewed, this adjustment being with respect to the path of movement of the needle of the sewing machine and enabling proper blind stitching of materials of widely varying thicknesses; yet another feature of this invention is that the adjusting means includes motion-reducing connections and calibrated indicating means facilitating setting of the apparatus for the material to be blind stitched; a further feature of this invention is the provision of a spring-urged fold guiding arm for holding the material being sewed in the desired relationship with the guiding means; and still a further feature of this invention is that the guide plate and associated pressure member for guiding the material being sewed may both be readily swung out of operative position to enable the machine to be used for ordinary sewing without the necessity of removing the blind stitching apparatus. Other features and advantages of this invention will be apparent from the following specification and the drawings, in which:

Figure 1 is a side elevational view of the head and a portion of the bottom of a sewing machine including blind stitching apparatus embodying my invention; Figure 2 is a fragmentary enlarged detail view of a portion of the apparatus shown in Figure 1; Figures 3, 4 and 5 are illustrative of material during and after blind stitching of a hem therein, Figure 3 being a sectional view of the material immediately after a stitch has been made therein, Figure 4 being a similar sectional view of the material unfolded into the shape in which it is worn, and Figure 5 being a fragmentary view of the surface of the material indicating the path of the stitching; Figure 6 is a plan view of the throat plate and a portion of a bed of a sewing machine together with blind stitching apparatus embodying my invention as illustrated in Figure 1; Figure 7 is a sectional view along the line 7—7 of Figure 6; Figure 8 is

2

a section view along the line 8—8 of Figure 6; Figure 9 is a sectional view along the line 9—9 of Figure 6; Figure 10 is a side elevational view of my special presser foot and guiding arm in blind stitching position; Figure 11 is a front elevational view of the parts shown in Figure 10; Figure 12 is a view along the line 12—12 of Figure 10; and Figure 13 is a view similar to Figure 11, but with the guiding arm up in inoperative position.

10 In finishing the bottoms of men's trousers, the hems of women's skirts and the like, it is good tailoring practice to effect the desired hemming by blind stitching. In blind stitching, the thread is run clear through the upturned piece of material which will be concealed, but is run into and out of the piece of material on the outside of the seam, rather than through this material, so that the stitching is not visible from the outside in the finished garment. Blind stitching by hand is 15 a slow and laborious process; and blind stitching of articles of tubular design on sewing machines has always heretofore involved the use of special blind stitching sewing machines with tubular knees and special beds, these machines being expensive and not being suitable for ordinary sewing, so that they lay idle most of the time.

I have devised and am here disclosing and claiming an attachment which converts the ordinary sewing machine into a blind hemmer; which 20 enables blind hemming to be done very quickly and easily on materials of various thicknesses; and which is so arranged that it does not in any way impede or hinder normal use of the sewing machine for conventional stitching. I preferably embody my invention in an attachment comprising parts which replace the conventional throat plate and slide plate of the ordinary sewing machine, it only being necessary to loosen a couple of screws holding the conventional throat plate in place, to remove it, to replace it and its associated slide plate with my attachment; which replaces the conventional presser foot of the machine with my special presser foot and guiding arm; and which replaces the conventional dog or feeder members with similar but longer members. My attachment preferably consists of three units, one comprising a throat plate, a slide or mounting plate slidably associated with the throat plate, actuating means for effecting 25 precision adjustments of the position of the mounting plate with respect to the throat plate, and a material guiding plate pivotally mounted on the mounting plate; another comprising a presser foot with a guiding arm spring-urged toward the guiding edge of the guiding plate; and

the third comprising the replacement dog or feed members.

In the particular embodiment of my invention illustrated herewith, a conventional sewing machine is partially illustrated, referring more particularly to Figure 1, this comprising a metal bed 10 mounted on a wooden base or table arrangement 11, and a conventional head 12 having a reciprocable needle carrier 13 in which a needle 14 is mounted for longitudinally reciprocable movement. A presser bar or presser foot, which will be more fully described later, serves to hold down the material being sewed; and a feed comprising the horizontally reciprocable toothed members 16 and 17 (best seen in Figure 6) serves to move the material in desired synchronism with needle reciprocation. These parts of a sewing machine will for the most part not be further described here, it being understood that my blind stitching attachment may be used with the conventional sewing machine.

As may be best seen in Figures 6-9, the throat plate 18 is of conventional shape, and is provided with a throat hole or opening 18a in which the needle is reciprocable. Immediately to the left of the throat plate (speaking with respect to the positions of the parts as shown in Figure 6) is a slide plate or mounting plate here identified as 19. This plate has soldered or otherwise rigidly attached to its bottom a pair of slide members 20 and 21, slidable in channels 22 and 23 rigidly mounted on the bottom of the throat plate 18, as may be best seen in Figure 9. The plate 19 is thus so mounted, with respect to the throat plate 18, that it is movable toward and away from this latter plate, in the same plane as the plate, through a limited range of movement. A guide plate 24 is pivotally mounted on the mounting member by appropriate brackets and rivets best seen in Figure 8, the rivets being identified as 25 and 26. These provide a mounting such that the guide plate 24 may be readily and quickly swung from an operative position as shown in the drawings to an inoperative position, this latter position being the result of swinging the guide plate about 180° counter-clockwise, speaking with respect to the positions of the parts as shown in the drawings. That is, pivoting of the guide plate 24 about an axis perpendicular to and spaced from the direction of movement of the needle 14 enables the guide plate to be quickly and easily moved from a position where its guiding edge 24a is closely adjacent the path of needle movement to a position where the plate is swung completely out of the way and substantially flat with the bed, so that there is no hindrance to normal sewing operations with the machine.

The way in which my attachment facilitates blind stitching and more particularly blind hemming will be best understood from a consideration of Figures 2-5, inclusive. Referring first to Figure 2, it will be seen that the material to be hemmed, as the bottom of a trouser leg here identified as 28, has a portion 28a overlying the guide plate 24, a portion 28b bent around the guiding edge 24a of the guide plate, a portion 28c extending back to the left under the guide plate, another curved or folded portion 28d, and a straight portion 28e extending back under the portion 28c and slightly out beyond the needle, these portions 28c and 28e lying on each other between the throat plate 18 and the guide plate 24. The material is so placed, during this folding, that the wrong side of the material faces upwardly in the part 28a, downwardly in the part 28c and upwardly again in the

part 28e. The guiding edge 24a of the guide plate is preferably spaced from the center of the path of movement of the needle 14 by a distance equal to about $\frac{1}{2}$ the thickness of the material, so that during the sewing operation the needle pierces the folded end portion 28b in the manner shown, and then passes straight through the right-hand end of the portion 28e of the material. The fold 28b of the material is held in proper relation to the guiding edge 24a of the plate 24 by the arcuate surface of a pressure shoe 49a at the end of a guiding arm mounted on my special presser foot, the guiding arm and presser foot being best seen in Figures 10 to 13, and more fully described later.

As the material is moved beyond the stitching point, it appears as illustrated in Figure 3, the parts of the material being stitched together by the thread 29. When the hem has been finished and the fold or bend 28b is straightened out, the material appears as shown in Figure 4 in cross section, and in Figure 5 in elevation, the stitching being shown in dotted lines because it is not visible through the right side of the material. It will be apparent that the curved or bent portion 28d becomes the bottom end of the trouser leg, the right side of the material being up as is illustrated in Figure 4, and the stitches formed by the thread 29 coming out of the material only on the wrong side. The fact that this arrangement enables the wrong side of the material to be up when it is being sewed, as in Figure 2, enables the material to be handled without having to slip it over a tubular knee or otherwise get part of it underneath the throat plate.

It will be immediately apparent that the spacing of the guiding edge 24a of the guide plate with respect to the path of needle movement must vary with different thicknesses of material. With the relatively thick material shown in the drawings for the purposes of clearly illustrating my invention, the space between the guiding edge 24a and the needle 14 may be fairly substantial. With thinner material, however, this spacing would have to be decreased in order to ensure passage of the needle through approximately the center of the folded or bent portion 28b. In order accurately and properly to adjust the spacing between the guiding edge and the needle, I provide, for moving the mounting member 19 and plate 24 toward and away from the path of the needle, actuating means which includes motion-reducing connections. The pressure shoe, being on the end of a pivotally mounted, spring-urged, arm, automatically accommodates itself to various thicknesses of material and various positions of the guiding plate.

Referring now more particularly to Figures 6 and 7, it will be seen that the mounting plate 19 has extending from the left side thereof an extension portion 30, which may be integral with the mounting plate or a separate piece riveted or otherwise permanently attached thereto. Pivotally mounted under the mounting plate, for movement about the axis 31, is a long lever 32, rigidly connected to a short lever 33, the arrangement being in the form of a bell crank. The short lever has its outer end pivotally connected at 34 to a connecting link 35 pivotally connected to the throat plate at the point 36. It will be readily seen that movement of the outer end of the lever 32 through a given distance effects movement of the mounting plate 19 toward or away from the throat plate 18, this latter movement being only a very small frac-

tion, as $\frac{1}{16}$, of the movement of the outer end of the lever 32. Since the guide plate 24 is carried on the mounting plate 19, movement of the outer end of the lever 32 enables precise adjustment of the spacing between the guiding edge 24a and the path of movement of the needle 14.

In order to facilitate movement of the outer end of the lever 32 and locking of the parts in any desired position, the lever has rigidly mounted therein near its outer end a threaded stud 38 passing up through a slot 30a and provided with a knurled knob or actuating member 38a. When it is desired to adjust the position of the guiding plate, the knob 38a is grasped, turned counter-clockwise sufficiently to unlock the mechanism, and the lever moved to the desired position, whereupon the knob is again tightened up to hold the actuating parts and guide plate in the position to which they have been set. To facilitate proper setting of the parts, the outer end of the lever 32 is turned back to form an indicating pointer 32a cooperating with an arbitrarily graduated scale on the arcuate outer end of the extension plate 30. This scale may be used by the operator accurately to predetermine the proper spacing for blind hemming materials of known types and weights.

Referring now more particularly to Figures 10 to 13, inclusive, my special presser foot and guiding arm attachment will be more fully described. The presser foot 40 comprises a substantially conventional foot portion 40a and a vertical shank portion 40b terminating in an attachment portion with two slots 40c and 40d. The shank is adapted to be mounted on a conventional presser foot supporting member 41 in either of two positions depending upon which mounting slot is used. A thumb nut screw 42 is threaded into the lower end of the supporting member 41, and is adapted to be received in one or the other of the two mounting slots. When the stud is in the slot 40d as illustrated in the drawings, the presser foot is in what may be termed blind stitching position; but when normal sewing is to be done the thumb nut is loosened and the presser foot so mounted that this stud lies in slot 40c.

Since these slots are spaced apart (five-sixteenths inch from center to center in the particular embodiment illustrated in the drawings, although this distance might vary on different machines), this results in two different corresponding positions of the presser foot. Referring more particularly to Figure 12, it will be seen that when the mounting is as illustrated in solid lines, the needle hole 18a is just slightly beyond the end of the presser foot; whereas, when slot 40c is used for mounting, the needle hole 18a is in the position shown in dotted lines in this figure, for conventional sewing. In order to provide proper feeding of the material in either of these two different positions of the presser foot, the toothed feed means 43 is made longer than is normally the case, and moves in a correspondingly longer slot in the throat plate 18.

At the back of the presser foot 40 near the junction of the foot portion with the upwardly extending shank, a transverse opening receives a threaded shaft 44 providing an extension of a mounting bracket 45. This shaft is held in place by a knurled nut 46, with spring washer means here identified as 47 between the nut and the shank of the presser foot, this means being here shown as two dished washers of spring metal. The mounting bracket 45 has mounted on it,

for pivotal movement about an axis provided by a rivet 48 at right angles to the shaft 44, a guiding arm here identified as 49. This guiding arm is provided at its outer end with a pressure shoe 49a which, as has been described earlier and as may be best seen by reference to Figure 2, is adapted to press against the fold of the material bent around the guiding edge 24a of the guiding plate. A wire spring 50 is coiled around the rivet 48 and so arranged as to constantly urge the arm in a clockwise direction (speaking with reference to the position of the parts as shown in Figure 12), so as to cause the shoe 49a to maintain constant pressure on the material feeding along the guiding edge of the guiding plate 24. When it is desired to do conventional sewing the guiding arm is swung about the axis provided by the shaft 44 to the vertical position shown in Figure 13, where it is out of the way and does not interfere with normal stitching. That is, when blind stitching is being done the presser foot and guiding arm are in the position shown in Figures 10, 11 and 12; whereas when it is desired to do conventional stitching, the presser foot is mounted in its other mounting slot 40c and the guiding arm is swung up out of the way into the position shown in Figure 13. The spring washer 47 provides frictional means for holding the guiding arm in either of two positions.

As will be readily apparent from reading the foregoing description, I have provided attachment means, in the form of a unit replacing the conventional throat plate, a unit replacing the conventional presser foot, and feed dogs replacing the conventional dogs, which converts any ordinary sewing machine into a blind stitching machine or blind hemmer. With my attachments blind stitching can be done quickly, easily and accurately. Yet the attachments are so arranged that the parts used in blind stitching (speaking more particularly of the guiding plate 24 and the guiding arm 49) may be quickly and easily flipped or pivoted out of blind stitching position into an inoperative position which permits conventional sewing to be done on the machine without the necessity of removing the attachments.

While I have shown and described certain embodiments of my invention, it is to be understood that it is capable of many modifications. Changes, therefore, in the construction and arrangement may be made without departing from the spirit and scope of the invention as disclosed in the appended claims.

I claim:

1. In a sewing machine having a reciprocal needle, and a presser foot blind stitching apparatus of the character described, including: a guide member adapted to have a material-guiding edge closely adjacent the path of movement of the needle; a mounting member having the guide member pivotally mounted thereon, about an axis perpendicular to and spaced from the line of movement of the needle, the mounting member being movable in a plane perpendicular to the direction of movement of the needle; actuating means for moving the mounting member to adjust precisely the position of the guiding edge of the guide member with respect to the path of movement of the needle, the actuating means including a manually movable actuating member and a motion-reducing actuating connection between said actuating member and the mounting member; a guiding arm pivotally mounted on the
- 60
- 65
- 70
- 75

presser foot for movement about two axes at right

angles to each other, one end of the guiding arm being provided with a pressure shoe adapted to lie adjacent said material-guiding edge for pressing the material being sewed against the guide means; and spring means for urging the pressure shoe towards the guide means.

2. Apparatus of the character claimed in claim 1, including means for locking the guide means in any position to which it may be adjusted.

3. In a sewing machine having a reciprocal needle, a slotted throat plate and a presser foot supporting member, apparatus including: a presser foot having means for connection to said supporting member in two spaced positions longitudinally of the line of stitch; a guiding arm pivotally mounted on said presser foot and having an end adapted to lie in front of one end of the presser foot; and feed means operable in the slots in said throat plate and of sufficient length to effect proper feeding of the material being sewed in either position of the presser foot.

4. Blind stitching apparatus of the character described for use in a sewing machine having a reciprocal needle and a presser foot supporting member, including: a throat plate having slots therein for feed means and a hole adapted to receive the end of the needle; a guide member adapted to have a material-guiding edge closely adjacent the path of movement of the needle; a mounting member having the guide member pivotally mounted thereon, about an axis perpendicular to and spaced from the line of movement of the needle, the mounting member being movable in a plane perpendicular to the direction of movement of the needle; actuating means for moving the mounting member to adjust precisely the position of the guiding edge of the guide member with respect to the path of movement of the needle, the actuating means including a manually movable actuating member and a motion-reducing actuating connection between said actuating member and the mounting member; a presser foot having means for connection to said supporting member in two spaced positions longitudinally of the line of stitch; a guiding arm pivotally mounted on said presser foot and having an end adapted to lie in front of one end of the presser foot; spring means for urging said end of the guiding arm toward said material-guiding edge to press the material being sewed thereagainst; and feed means operable in the slots in said throat plate and of sufficient length to effect proper feeding of the material being sewed in either position of the presser foot.

5. In a sewing machine having a reciprocal needle and presser foot supporting means, apparatus of the character described for selectively enabling blind stitching or conventional stitching, including: a throat plate having a hole adapted to receive the end of the reciprocal needle; a guide member pivotally mounted on the plate and movable between two limiting positions, the guide member when in one position having a material-guiding edge closely adjacent the path of movement of the needle and when in the other position presenting no interference with conventional stitching; a pivotally mounted pressure member movable between two limiting positions and adapted to hold the material against the guiding edge of the guide member when in one position and when in the other position presenting no interference with conventional stitching; actuating means for precisely adjusting the position of one of said members with respect to the path of movement of the member; spring means

operative on the other member to urge it toward the adjustable member; a presser foot movable between two positions, one closely adjacent the path of movement of the needle for conventional sewing and the other further therefrom for blind stitching; and feed dogs cooperating with the pressure foot in both of its positions.

6. In a sewing machine having a reciprocal needle, presser foot supporting means, and feed dogs, apparatus of the character described for selectively enabling blind stitching or conventional through-and-through stitching, including: a supporting plate adapted to be attached to the sewing machine; a first guide member both slidably and pivotally mounted with respect to the plate, the pivotal mounting providing for movement about a horizontal axis between two limiting positions, this guide member when in one position having a material-guiding portion closely adjacent the path of movement of the needle, the construction and mounting being such that said portion is freely movable vertically during stitching, the guide member when in the other position presenting no interference with conventional stitching; a second pivotally mounted guide member movable between two limiting positions and adapted to hold the material against the guiding portion of the first guide member when in one position and when in the other position presenting no interference with conventional stitching; spring means operative on said second guide member, when in material-guiding position, to urge it toward the first guide member; and manually operable motion-reducing actuating means for slidably moving and precisely adjusting the position of said first guide member.

7. In a sewing machine having a reciprocal needle, presser foot supporting means, and feed dogs, apparatus of the character described for selectively enabling blind stitching or conventional through-and-through stitching, including: a supporting plate adapted to be attached to the sewing machine; a first guide member both slidably and pivotally mounted with respect to the plate, the pivotal mounting providing for movement about a horizontal axis between two limiting positions, this guide member when in one position having a material-guiding portion closely adjacent the path of movement of the needle, the construction and mounting being such that said portion is freely movable vertically during stitching, the guide member when in the other position presenting no interference with conventional stitching; a second pivotally mounted guide member movable between two limiting positions and adapted to hold the material against the guiding portion of the first guide member when in one position and when in the other position presenting no interference with conventional stitching; spring means operative on said second guide member, when in material-guiding position, to urge it toward the first guide member; manually operable motion-reducing actuating means for slidably moving and precisely adjusting the position of said first guide member; and a presser foot movable longitudinally of the line of stitch between two positions, one closely adjacent the path of movement of the needle for conventional sewing and the other further therefrom for blind stitching, the presser foot being adapted to cooperate with the feed dogs in both of its positions.

8. In a sewing machine having a reciprocal needle, presser foot supporting means, and feed dogs, apparatus of the character described for

enabling blind stitching, including: a supporting plate adapted to be attached to the sewing machine; a first guide member both slidably and pivotally mounted with respect to the plate, the pivotal mounting providing for movement about a horizontal axis, this guide member when in one position having a material-guiding portion closely adjacent the path of movement of the needle, the construction and mounting being such that said portion is freely movable vertically during stitching; a second pivotally mounted guide member movable between two limiting positions and adapted to hold the material against the guiding portion of the first guide member when in one position; spring means operative on said second guide member, when in material-guiding position, to urge it toward the first guide member; and manually operable motion-reducing actuating means for slidably moving and precisely adjusting the position of said first guide member.

9. In a sewing machine having a reciprocal needle, a presser foot, and feed dogs, blind stitching apparatus of the character described, including: a first guide member adapted to have a portion closely adjacent the path of movement of the needle, this member being movable for adjustment in a direction perpendicular to the direction of movement of the needle, and having its guiding end freely movable vertically; actuating means for precisely adjusting the position of the first guide member with respect to the path of

movement of the needle, the actuating means including a manually movable actuating member and a motion reducing actuating connection between said actuating member and said guide means; a second guide member adjacent said first guide member for pressing the material being sewed thereagainst; and spring means for urging the second guide member toward the first guide member.
